UNITED STATES PATENT OFFICE

JOSEPH E. FALCK, OF PITTSBURGH, PENNSYLVANIA, ASSIGNOR TO NATIONAL CASKET COMPANY, INCORPORATED, OF PITTSBURGH, PENNSYLVANIA, A CORPORATION OF NEW YORK

CLAMPING MEANS FOR CASKETS

Application filed May 10, 1927. Serial No. 190,159.

The present invention relates broadly to caskets, and more particularly to metal caskets and to improved means for use in connection therewith for effectively sealing the same.

The demand for metal caskets is a gradually increasing one, due to the inherent characteristics thereof, but even at the present time the means available for sealing the same, while accomplishing a complete sealing, have not been altogether satisfactory. The present invention has for one of its objects, the provision of an improved casket structure and improved clamping means for use in connection therewith, by reason of which a more desirable construction is provided.

In the accompanying drawings there is shown for purposes of illustration only, a preferred embodiment of my invention, it being understood that the drawings do not define the limits of the invention, as changes in the construction and operation disclosed therein may be made without departing either from the spirit of the invention or the scope of my broader claims.

In the drawings,

Figure 1 is a partial transverse sectional view through a portion of a casket, constructed in accordance with the present invention and illustrating in elevation an improved clamping means in position thereon,

Figure 2 is an elevational view of the clamp shown in Figure 1 looking at the same from the front thereof,

Figure 3 is a view partly in section and partly in elevation along the line III—III of Figure 2, and,

Figure 4 is a transverse sectional view on the line IV—IV of Figure 3, looking in the direction of the arrows.

In accordance with the present invention, there may be provided a metal casket, the main body portion of which may be constructed in any desired manner. The upper portion 2 of the main body is preferably formed with an inwardly projecting portion providing a shelf 3 terminating in an upstanding edge 4, the extreme upper end of which is bent inwardly, outwardly and then downwardly, as clearly illustrated in Figure 3 to provide an

outwardly projecting portion 5 with a shoulder 6.

The cover 7 may likewise be of any desired construction, and at its lower edge is shaped to provide a channel 8 for the reception of a packing strip 9. The channel constitutes an outwardly projecting portion on the cover and is provided with a shoulder 10 generally similar to the shoulder 6 on the body. These two outwardly projecting portions are adapted, when the cover is assembled, to lie one above the other, as clearly appears from Figure 1, with the shoulders 6 and 10 in vertical alignment in substantially the same plane.

When the parts have been assembled so that they occupy the positions referred to, it is necessary, in use, to provide some means for clamping the cover in position in such manner that the packing strip 9 will effect a hermetic closure between the body and the cover. Heretofore, where it has been desired to accomplish this result without projection of the fastening means into the body of the casket, a comparatively expensive structure has been necessitated. In accordance with the present invention these difficulties are obviated by the provision of the two outwardly projecting portions on the cover and body, so arranged that they may effectively cooperate with an improved clamping means 11.

This clamping means comprises a body portion 12, preferably of generally channel shaped cross section, having formed thereon one or more clamp portions 13, preferably formed with downwardly inclined clamping faces 14. Slidably mounted within the body 12 is a clamping member 15 provided with a clamping projection 16 having an upwardly inclined face 17, as clearly appears from Figure 3 of the drawings, thereby providing a substantially C shaped clamp.

For effecting movement of the clamping member 15 there may be provided a screw 18 having threaded engagement with the member 15, whereby upon rotation of the screw the member 15 is moved axially of the same in one direction or the other. This screw may be provided with an enlarged head 19 formed with a peripherally extending groove 20, with which cooperates a trans-

versely extending pin 21 constituting an interlocking engagement such that disengagement of the screw and body is prevented. After a clamping member 15 has been threaded into position, the lower end of the screw 18 may be peened over, or otherwise distorted, as indicated at 22 to prevent accidental loss of such clamping member.

It will be apparent to those skilled in the art that with a construction as herein illustrated, a cover may be readily clamped in position without any possibility of leakage into or from the body of the casket, such as is apt to occur where the body is perforated, and without any possibility of corrosion or other deterioration of the clamping means, such as occurs when the clamping means is subject to the conditions within the casket.

20 The provision of the shoulders 6 and 10 on the outwardly projecting portions of the cover and casket in conjunction with the inclined faces on the clamping projections precludes possibility of outward movement of 25 the clamping means, and insures maximum efficiency thereof at all times. It will also be understood that any desired number of clamping means may be applied, as required.

Certain advantages of the present invention arise from the provision of a casket which 30 may be constructed without perforations of any nature whatever for the reception of the cover clamping means.

Other advantages of the invention arise 35 from the provision of a casket structure having both the cover and body formed with outwardly projecting portions adapted for effective cooperation with detachable clamping means.

40 Still further advantages of the invention arise from the use of clamping means which may be quickly slipped into and out of position, and which are of such construction that they embrace the outwardly projecting portions 45 on the body and cover and effectively hold the cover in position at point or points externally of the casket body.

I claim:-

1. Clamping means for caskets, comprising 50 a channel shaped body of substantially uniform cross section having open end portions freely open throughout substantially the entire width of the channel, a screw in said body projecting through one end, means 55 for interlocking the screw with the body, and engaging means operable by the screw and movable through the other end of said body.

2. Clamping means for caskets, comprising 60 a channel shaped body of substantially uniform cross section having open end portions freely open throughout substantially the entire width of the channel, a screw in said body projecting through one end, said screw having an enlarged bearing portion within 65 said body, means cooperating with said en-

larged bearing portion for interlocking the screw with the body, and engaging means operable by said screw and movable through the other end of said body.

In testimony whereof I have hereunto set 70 my hand.

JOSEPH E. FALCK.
